UNITED STATES PATENT OFFICE.

JOHN SACHAR, OF KATO, PENNSYLVANIA, ASSIGNOR OF ONE-HALF TO ANTONINE ULANITZKI, OF RAMEY, PENNSYLVANIA.

EQUILIBRATOR FOR BOATS.

1,261,168.

Specification of Letters Patent.

Patented Apr. 2, 1918.

Application filed April 25, 1916, Serial No. 93,472. Renewed February 28, 1918. Serial No. 219,730.

To all whom it may concern:

Be it known that I, JOHN SACHAR, a subject of the Emperor of Austria, residing at Kato, in the county of Center and State of Pennsylvania, have invented certain new and useful Improvements in Equilibrators for Boats, of which the following is a specification.

This invention relates to certain new and useful improvements in equilibrators for boats.

The primary object of the invention is the provision of adjustable outriggers for ships adapted for engaging the surface of the water imparting stability to the craft, adjustable wave-piercing members being provided therefor.

A further object is to provide flat wave-engaging outriggers adjustably arranged at the bow and stern of a boat and having anti-frictional engagement therewith, the same being adapted for maintaining the equilibrium of the boat during a storm or in rough weather without impeding the progress thereof.

A still further object is the provision of an outrigger for a boat anti-frictionally shiftably contacting the side thereof and radially adjusted in height from the deck of the boat, the outrigger being arranged at its free end with an adjustable wave-engaging parting member facilitating the progress of the boat therethrough.

With these general objects in view and others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—

Figure 1 is a side elevation of a boat provided with the present device.

Fig. 2 is a top plan view thereof.

Fig. 3 is an enlarged elevational view of the bow portion of the boat with the device partially broken away, the wave spreader being illustrated by dotted lines in its depressed operative position.

Fig. 4 is a top plan view thereof.

Fig. 5 is a vertical detail sectional view

showing the anti-friction means for one of the outriggers.

Fig. 6 is a top plan view of the same, and,

Fig. 7 is an enlarged detail sectional view of one of the vertical adjusting means for the device.

The present stabilizing device or equilibrator is serviceable in connection with any large boat or vessel and is herein illustrated in connection with the boat 10, the said boat being provided with one of the same adjustably attached to both its bow 11 and stern 12. Each of the outriggers is provided upon its lateral edge with a depending flange 34.

The bow device illustrated in Figs. 3 and 4 of the drawings consists of a substantially rectangular table form of outrigger 13 having a V-shaped cut-away portion or notch 14 in its rear end adapted for receiving the boat bow 11, the outrigger being vertically adjustable thereon. The bow 11 is provided with a longitudinal slot 15 therein adapted to receive an anti-friction ball member 16

which is seated within a depression 17 in the adjacent edge of the outrigger 13 and retained by means of oppositely arranged plates 18 providing a form of cage as best illustrated in Figs. 5 and 6 of the drawings.

Operating screws 19 are arranged at opposite sides of the bow 11 having their lower ends swiveled in brackets 20 carried by the sides of the boat and journaled in upper brackets 21 also carried by the boat. Opposite bosses 22 are provided upon the edges of the outrigger notch 14 and the screws 19 are threaded therethrough while hand wheels 23 are provided upon the tops of the said screws adjacent the boat deck 33.

By this arrangement, it will be clear that by turning the hand wheels 23 in the required direction, the outrigger 13 may be elevated and lowered as found desirable, the shifting of the outrigger 13 being rendered easy by means of the ball bearing 16.

It will be understood that the stern outrigger 24 is of substantially the same construction as the said bow outrigger 13 so that further detailed description thereof will be unnecessary, the identical parts being indicated by the same reference characters as employed in connection with the said bow outrigger, it being noted however, that the inner edge 25 of the stern outrigger 24 is of

arcuate form to correspond to the boat stern 12 while as before noted, the inner edge 14 of the bow outrigger is of a shape to conform to the bow 11. In operation, the outriggers 13 and 24 will be adjusted by means of the hand wheels 23 to a position at substantially the level of the water when the latter is calm and whereby during a storm or in the event of high waves, the said outriggers will assist in maintaining the boat 10 upon an even keel.

A wave-piercing device is provided upon the free outer edge 26 of each of the outriggers consisting of a pyramidal block 27 hinged as at 28 centrally of the said edge 26 and provided with an adjusting lever 29 pivoted to an opposite point upon the base thereof as at 30 and adjustably secured to an upright post 31 of the outrigger by means of a removable bolt 32.

It will thus be understood that when desired for use, the outriggers 13 and 24 being adjusted to the level of the water, the wave-piercing members 27 are lowered as shown by dotted lines in Fig. 3 of the drawings so that the apices thereof are substantially in the same plane as the outriggers and whereby during the travel of the boat 10, the cone-shaped blocks 27 pierce the waves, breaking the same and preventing the force of the waves from beating upon the boat and in a manner preparing the water for the outriggers to float thereon.

While the form of the invention herein shown and described is what is believed to be the preferred embodiment thereof, it is nevertheless to be understood that various forms, modifications and arrangements of the parts may be made without departing 40 from the spirit and scope of the invention as claimed.

What I claim as new is:—

1. A device of the class described, comprising in combination with a boat having a vertical groove in the bow thereof, a flat outrigger having a cut-away inner edge shiftably positioned upon the boat bow, an anti-friction member gathered by the inner end of the said cut-away portion in operative engagement with the said groove,

threaded bosses carried upon the outrigger adjacent the said cut-away portion thereof, adjusting screws swivelly mounted at opposite sides of the boat and positioned through the said bosses, and operating hand wheels 55 carried by the tops of the said screws adjacent the deck of the boat.

2. A device of the class described, comprising in combination with a boat having a vertical groove in the bow thereof, a flat 60 outrigger having a cut-away inner edge shiftably positioned upon the boat bow, an anti-friction member gathered by the inner end of the said cut-away portion in operative engagement with the said groove, 65 threaded bosses carried upon the outrigger adjacent the said cut-away portion thereof, adjusting screws swivelly mounted at opposite sides of the boat and positioned through the said bosses, operating hand wheels carried by the tops of the said screws adjacent the deck of the boat, a cone-shaped block pivoted at one edge of its base to the outer edge of the said outrigger substantially centrally thereof, a post upon the said outrigger, and an operating lever pivoted at one 70 end to the base of the said block at a point opposite the hinging point thereof and having its other end adjustably attached to the top of the said post. 80

3. A device of the class described, comprising an outrigger, a cone-shaped block pivoted at one edge of its base to the outer edge of the said outrigger substantially centrally thereof, a post upon the said outrig- 85 ger, and an operating lever pivoted at one end to the base of the said block at a point opposite the hinging point thereof and having its other end adjustably attached to the top of the said post. 90

4. An equilibrator for boats comprising table-shaped outriggers having their inner edges cut-away corresponding to the form of the bow and stern of the boat, anti-friction means arranged between the central 95 points of the said cut-away portions and the boat, and vertical adjusting means for the said outriggers.

In testimony whereof I affix my signature:
JOHN SACHAR.
